UNITED STATES PATENT OFFICE.

TOM R. WALKER, OF ALEXANDRIA, LOUISIANA, ASSIGNOR TO WALKER PATENTS COMPANY, INC., OF ALEXANDRIA, LOUISIANA, A CORPORATION.

SHIPPING-CONTAINER BINDER.

Application filed January 19, 1928. Serial No. 82,315.

This invention aims to provide a binder which will protect the corners and angles of a shipping container completely, the binder being adjustable to fit containers of different sizes, and being so constructed that it will retain its place on a shipping container without resorting to the use of diagonal ties, or tacks, nails, or anything else of a like sort which engages the container, the article being clearly distinguished, in this respect, from common angle iron, reinforcements which are fastened to the box by securing elements which enter the box.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in perspective, a binder constructed in accordance with the invention, and mounted on a shipping container:

Figure 2 is a plan showing the blank out of which one of the arms of the corner bracket is made, parts being broken away;

Figure 3 is a plan showing the blank out of which two others of the arms of the corner bracket are made, parts being broken away;

Figure 4 shows the arm that is made out of the blank depicted in Figure 2;

Figure 5 is a perspective showing the two arms on the corner bracket that is made out of the blank depicted in Figure 3;

Figure 6 is a perspective showing one of the corner brackets of one set, parts being broken away;

Figure 7 is a perspective showing one of the corner brackets of the other set, parts being broken away;

Figure 8 is a perspective showing one of the connection and extension pieces.

The binder forming the subject matter of this application is made of metal and is adapted to be placed on a shipping con-

tainer 14 of any desired sort, for instance, the box shown in my co-pending application Serial Number 82,314 filed on the 19th day of January, 1926; although the binder may be used, of course, upon any kind of a box or container, whether of wood, metal, or woven material.

The binder embodies a set of corner brackets 1 and a set of corner brackets 2, each bracket 1 comprising transverse arms 3 and 4, and each bracket 2 comprising transverse arms 5 and 6, each of the brackets 1 including a longitudinal arm 7, and each of the brackets 2 comprising a longitudinal arm 8. The arms 3, 4, 5, 6, 7 and 8 are in the form of angle members, each including rectangularly disposed flanges 9.

Each arm 3 or 7 or 4 of the bracket 1 is disposed at right angles to the other arms of that bracket, and each of the arms 8, 5 or 6 of the bracket 2 is disposed at right angles to the other arms of that bracket. The flanges of the arms of every angle bracket are supplied at their outer edges with trough-shaped longitudinally extended overhanging wings 10. Extension and connection pieces 11 are provided. The parts 11 are called connection elements, because they join and connect the corner brackets with each other. The parts 11 join the corresponding transverse arms 6—6 and 5—5 of the corner brackets 2, and join the corresponding arms 4—4 and 3—3 of the corner brackets 1, extension pieces also joining the longitudinal arms 7 of the brackets 1 with the longitudinal arms 8 of the corner brackets 2, the arms 9 being considerably longer than the arms 8, if desired, as clearly shown in Figure 1 of the drawings.

Each extension or connecting piece 11 comprises rectangularly disposed flanges 12 slidably engaged at their outer edges for adjustment with the wings 10 of the arms wherewith each extension piece cooperates. A means is provided for effecting a step by step adjustment between the extension or connecting pieces 11 and the various arms of the corner brackets, in a direction longitudinally of the extension pieces and the arms, this construction adapting one binder to many shipping containers of different sizes. It is to be observed that the step by step adjusting means, and the overhanging wings 10, constitute the sole mechanism for

holding the binder in place on a container— meaning thereby that when the binder is in place on the container 14, as shown in Figure 1, it will stay there, by its inherent construction, and it being unnecessary to fasten any part of the binder to the container by nails, screws or any other kind of securing elements, it being equally unnecessary to connect spaced parts of the binder, diagonally, transversely, or in any other way, by ties, such as wires, straps and the like. In other words, the wings 10 hold the arms and the extension pieces together against separation transversely, and the aforesaid 10 step by step mechanism holds the extension pieces and the arms against separation lengthwise. The step by step mechanism, upon which considerable emphasis has been laid hereinbefore, may embody racks 15 on 20 the flanges 12 of the extension pieces 11, and resilient inwardly inclined pawls 16, struck from the flanges 9 of the arms and adapted to engage releasably with the racks 15, in a way which will be understood 25 readily by those skilled in the art. The racks 15 at the respective ends of the member 11 face in opposite directions, and in order to prevent the member 11 from sliding too far in one direction, whilst the article is being assembled, and permitting one 30 set of the pawls 16 to come into contact with racks upon which they can not hold, the member 11 is supplied intermediate its ends with stops 30 adapted to cooperate with 35 the ends of the arms.

The particular way in which the various arms are connected and constructed may be varied, but, if desired, recourse may be had to the blank 17 shown in Figure 3, the 40 blank being provided in one edge with a V-shaped notch 18, and being supplied in its opposite edge with a shallow rectangular notch 19. The blank is turned over on longitudinal lines 20 to form the wings 10, the blank being folded transversely, as at 45 21, at the apex of the notch 18, to bring the edges of the notch 18 together as shown at 22, the notch 19 becoming, as shown in Figure 5, an opening 23 located at the inner 50 ends of two of the arms and interrupting the overhanging wings 10. Referring to Figure 2 there is shown a blank 24 having an outstanding tongue 25 at one end. The blank 24 is folded along a longitudinal line 26 55 to form the flanges, and is turned along longitudinal lines 27 to form the wings 10. The tongue 25 is disposed at right angles to the flanges and closes the end of the angle member as shown at 28 in Figure 4. The end 60 of the member shown in Figure 4 is inserted into the angle of the member shown in Figure 5, and the parts may be held together by spot welding or otherwise, to constitute the corner bracket shown in Figure 6, or 65 the corner bracket shown in Figure 7.

The device claimed, shown and described, is simple in construction, easily assembled, and inexpensive. It may be used on any style box made of any material, whether wood, metal, fibre, paper or cloth, netting or 70 mesh work. By the use of the device described, a box may be constructed of straight panel pieces without fastening devices of any kind, and may be held together and protected adequately. The article is almost 75 indestructible and adds greatly to the carrying strength of any box on which it is used. Space is economized, because boxes reinforced by the device forming the subject matter of this application, may be stacked 80 to great height, without crushing. The article is collapsible and may be bundled and shipped in small compass, and it has a returnable or resale value. The fact that the article has a returnable or resale value can- 85 not be too strongly emphasized, as it saves cost of material, time and labor. This is important both to the consumer and to the manufacturer.

I claim:—

1. A shipping container binder embodying two sets of corner brackets, each bracket of each set comprising transverse arms and a longitudinal arm, each arm being in the form of an angle member including rectangularly disposed flanges, each arm of each corner bracket being disposed at right angles to the other arms of the same bracket, the flanges of each arm of each angle bracket having trough-shaped longitudinally extended overhanging wings, extension pieces joining the corresponding transverse arms of the corner brackets of each set, and extension pieces joining the longitudinal arms of corresponding corner brackets of the respective sets, each extension piece comprising rectangularly disposed flanges slidably engaged for adjustment with the wings of the arms wherewith each extension piece cooperates, and means for effecting a step by step adjustment between the extension pieces and the arms, in a direction longitudinally of the extension pieces and the arms, said means and the wings constituting the sole mechanism for holding the binder in place on a container.

2. A shipping container binder, constructed as set forth in claim 1, and further characterized by the fact that the means for effecting a step by step adjustment embodies racks on the extension pieces, and resilient pawls on the arms, the pawls being releasably engaged with the racks.

3. In a device of the class described, a corner bracket comprising arms disposed at an angle to each other, each arm including flanges, one flange having a V-shaped notch, the other flange being folded transversely to bring the edges of the notch together, the flanges having overhanging wings at their 125 130

outer edges, there being an opening through disposed in engagement with the flanges of the wings of said other flange, at the inner ends of the arms, and an angle member comprising flanges, one flange having a trans-

5 verse tongue closing the end of said angle member, and said end of the angle member being inserted into the opening and being

In testimony that I claim the foregoing 10 as my own, I have hereto affixed my signature.

TOM R. WALKER.
